CLAIM

I claim the ornamental design for a projection clock, as shown and described.

DESCRIPTION

- FIG. 1 is a Perspective view of a projection clock;
 FIG. 2 is another Perspective view thereof;
 FIG. 3 is a Front view thereof;
 FIG. 4 is a Rear view thereof;
 FIG. 5 is a Left view thereof;
 FIG. 6 is a Right view thereof;
 FIG. 7 is a Top view; and,
 FIG. 8 is a Bottom view thereof.
